P. G. MacGREGOR

FIRE EXTINGUISHER

Filed Oct. 13, 1924

INVENTOR
Peter G. Mac Gregor
BY
Lewis J. Doolittle
ATTORNEY

UNITED STATES PATENT OFFICE.

PETER G. MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE.

FIRE EXTINGUISHER.

Application filed October 13, 1924. Serial No. 743,348.

This invention relates to improvements in fire extinguishers, and especially to an improved extinguisher of the foam or two-solution type, which is adapted normally, that is when not being operated to cause ejection of foam, to rest upon the base portion thereof, but which is adapted to be reversed in position to cause commingling of the solutions therein to produce the fire-extinguishing foam under pressure sufficient to cause ejection thereof from the apparatus.

The object of the invention is the provision of sealing means for an inner liquid container including an inturned stopple seat in the form of an annular lip within said inner container, against which lip a stopple or seal is adapted to be pressed to effect positive sealing of said container, the operating or pressure means for said seal being mounted in the stand-forming cap which is normally the upper portion of the apparatus, but which serves as its base when the extinguisher is reversed for operation.

The abovementioned and other features of the invention not hereinbefore referred to will be hereinafter described and claimed and are illustrated in the accompanying drawings, in which Figure 1 is a view partly in vertical section and partly in side elevation of a fire extinguishing apparatus embodying the present invention. Figure 2 is a horizontal sectional view taken on line 2-2 of Figure 1.

Referring to the drawings, 2 designates a solution receptacle of a well-known type adapted normally, that is when not being operated to cause ejection of fluid, to rest upon a base portion 3 thereof, and which is provided with a cap 4 at the other end thereof adapted to provide a stand or rest for the extinguisher when the same is inverted to cause ejection of fire-extinguishing fluid. Said cap 4 may also be used as the base or stand for the extinguisher at the times when the liquids within the receptacle are not permitted to escape therefrom. At 5 is shown a flexible tube adapted for attachment to an outlet member 6 leading from the receptacle 2, said tube serving to permit directing of the fire-extinguishing fluid in the ordinary manner. The cap 4 is adapted for attachment to or detachment from the body of the receptacle 2, it being here shown as screw-threaded to the normal upper end of the said

receptacle. A compressible ring 7 is carried in said cap 4 and is adapted to be pressed against the upper lip 8 of the receptacle 2 to seal the mouth thereof and thereby prevent escape of fluid at such mouth. With this arrangement of parts it will be clear that liquid may be placed in the receptacle 2 and the cap 4 thereupon screwed down until the compressible ring 7 rests upon the lip 8 and seals said receptacle to prevent escape of liquid therefrom.

Heretofore in fire extinguishers of the two-solution type it has been customary to provide within the receptacle 2 a relatively short container adapted to hold a second or acid solution which is adapted to combine with the solution of the outer receptacle 2 to produce and eject a fire-extinguishing fluid or foam. This inner container ordinarily was located at the upper part of said receptacle and was held firmly in position by guides or by an enclosing frame, and the mouth thereof was provided with a gravity stopple adapted to cover it when the apparatus was in normal upright, that is, inoperative position. Reversing the position of the extinguisher served to cause the stopple to fall out of the mouth of the container, this resulting in escape of liquid therefrom into the outer receptacle and commingling therewith to form a fire-extinguishing foam which was forced out through the tube leading from the receptacle.

The apparatus of the present invention is not intended to permit commingling of the liquid of the inner container with that of the outer receptacle through the unseating of a gravity stopple of the inner container, but is designed to permit effective sealing of the outer receptacle 2 and an inner container 9 when the apparatus is not in operative condition, so that there will be no commingling at such times of the solutions carried therein and therefore no escape of fire-extinguishing foam from the apparatus regardless of the position in which the extinguisher is carried or placed. It is also designed to prevent escape of fluid at the cap 4 when the extinguisher is being operated.

The improved means herein may dispense with the use of a special positioning and supporting device for the inner container, this container 9 being guided loosely in the

receptacle neck and resting at all times upon the inner surface of the bottom thereof. The container 9 will ordinarily be in the form of a cylinder having a main lower liquid-containing portion 10 and an upper portion 11 having openings 11' therethrough adapted to permit egress of liquid therefrom when the extinguisher is inverted with the parts thereof in their operative positions.

10 The container near its upper end is formed with an inwardly projecting bead 9' which not only reinforces the upper portion of the container but also provides a ledge upon which is positioned and to which is secured 15 by solder an annular lip 12. The lip 12 projects inwardly and upwardly, the upper margin thereof being turned down at an angle thus forming a rounded seating surface adapted for the reception of a compressible 20 sealing disc 13 having means connected thereto adapted to force it down onto the lip 12 or to withdraw it from said lip. This operating means for the disc 13 is here shown 25 as a clamp-screw 14 threaded in the cap 4 and movable therein to raise or lower the sealing disc 13. Said clamp-screw 14 is operated by a hand-wheel 15, and a ball-and-socket connection 16 is employed between the clamp-screw 14 and the carrier-plate 30 16' of the sealing disc 13 to secure even pressure of said sealing disc against the lip 12. With the container resting firmly upon the bottom of the receptacle 2 and even pressure applied to the sealing disc 13, an 35 effective sealing of the container 9 is secured.

When it becomes necessary to operate the extinguisher the hand-wheel 15 is turned to withdraw the sealing disc 13 from the lip 12. This turning movement at the same time

carries a compressible washer 17 upward upward until it is compressed against the inner surface 18 of the cap 4 to seal the same at this point. The extinguisher may now be reversed in position to effect commingling of the two liquids, which will result in the 45 formation and ejection of a fire-extinguishing fluid or foam from the tube 5, without leakage at the cap 4 at either of the points 7 or 18.

In order that the cap 4 may serve as a 50 base for the extinguisher whenever it is so desired, I have shown it of such proportions that it will at all times and under all conditions of service extend beyond the hand-wheel 15, even when said hand-wheel has 55 been withdrawn to its outward limit of movement to effect sealing of the cap 4 at the point 18 at a time when the extinguisher is to be put into operation to discharge its fire-extinguishing foam.

What I claim is:

In a fire extinguisher, a liquid container of substantially uniform diameter throughout its length having openings in its wall near the top and formed with an inwardly 65 pressed bead in its wall below said openings, an annular lip positioned upon and secured to said bead within said container, said lip extending inwardly and downwardly thereby forming a seating surface, and a stopple having a diameter substantially equal to the inside diameter of said container and adapted to seat upon said seating surface.

Signed at Newark, in the county of Essex, and State of New Jersey, this 29th day of 75 September, A. D. 1924.

PETER G. MacGREGOR.
